US008522897B2

(12) **United States Patent**
Hall et al.

(10) **Patent No.:** US 8,522,897 B2
(45) **Date of Patent:** *Sep. 3, 2013

(54) **LEAD THE BIT ROTARY STEERABLE TOOL**

(75) Inventors: **David R. Hall**, Provo, UT (US); **Paula Turner**, Pleasant Grove, UT (US); **David Lundgreen**, Provo, UT (US); **Scott Woolston**, Provo, UT (US)

(73) Assignee: **Schlumberger Technology Corporation**, Houston, TX (US)

(*) Notice: Subject to any disclaimer, the term of this patent is extended or adjusted under 35 U.S.C. 154(b) by 382 days.

This patent is subject to a terminal disclaimer.

(21) Appl. No.: **12/557,679**

(22) Filed: **Sep. 11, 2009**

(65) **Prior Publication Data**

US 2010/0000794 A1 Jan. 7, 2010

Related U.S. Application Data

(63) Continuation-in-part of application No. 12/362,661, filed on Jan. 30, 2009, which is a continuation-in-part of application No. 11/837,321, filed on Aug. 10, 2007, now Pat. No. 7,559,379, which is a continuation-in-part of application No. 11/750,700, filed on May 18, 2007, now Pat. No. 7,549,489, which is a continuation-in-part of application No. 11/737,034, filed on Apr. 18, 2007, now Pat. No. 7,503,405, which is a continuation-in-part of application No. 11/686,638, filed on Mar. 15, 2007, now Pat. No. 7,424,922, which is a continuation-in-part of application No. 11/680,997, filed on Mar. 1, 2007, now Pat. No. 7,419,016, which is a continuation-in-part of application No. 11/673,872, filed on Feb. 12, 2007, now Pat. No. 7,484,576, which is a continuation-in-part of application No. 11/611,310, filed on Dec. 15, 2006, now Pat. No. 7,600,586, which is a continuation-in-part of application No. 11/278,935, filed on Apr. 6, 2006, now

Pat. No. 7,426,968, which is a continuation-in-part of application No. 11/277,394, filed on Mar. 24, 2006, now Pat. No. 7,398,837, which is a continuation-in-part of application No. 11/277,380, filed on Mar. 24, 2006, now Pat. No. 7,337,858, which is a continuation-in-part of application No. 11/306,976, filed on Jan. 18, 2006, now Pat. No. 7,360,610, which is a continuation-in-part of application No. 11/306,307, filed on Dec. 22, 2005, now Pat. No. 7,225,886, which is a continuation-in-part of application No. 11/306,022, filed on Dec. 14, 2005, now Pat. No. 7,198,119, which is a continuation-in-part of application No. 11/164,391, filed on Nov. 21, 2005, now Pat. No. 7,270,196.

No. 7,198,119 on Apr. 3, 2007, which is a continuation-in-part of U.S. patent application Ser. No. 11/164,391 filed on Nov. 21, 2005 and that issued as U.S. Pat. No. 7,270,196 on Sep. 18, 2007. All of these applications are herein incorporated by reference in their entirety and their priorities claimed.

BACKGROUND OF THE INVENTION

This invention relates to the field of tools used in directional drilling. More specifically, the invention includes a flexible portion disposed in a drill string to facilitate drilling inclined wellbores. The prior art includes several methods for steering a tool string. An embodiment of a bent sub system is generally depicted in FIG. 1a. In this embodiment, a drill string 2000 comprises a bent sub 2050 above the drill bit 2051. A hydraulic motor housed within a bore of a drill string component rotates the drill bit 2051 below the bent sub 2050. As drilling mud is passed through the drill string 2000, the motor turns in response to the flow and rotates a portion 2052 of the drill string 2000 below the bent sub 2050. A portion 2053 of the drilling string 2000 above the bent sub 2050 does not rotate from the motor, but slides through the wellbore as the drill bit 2051 advances into the earth. The bent sub 2050 directs the trajectory of the drill string 2000 in relation to an angle of the bent sub 2050.

2

An embodiment of a push-the-bit system is generally depicted in FIG. 1b. In this embodiment of a drill string 2100, an extendable pad 2150 is located above the drill bit 2151. Typically, there is more than one extendable pad oriented around an outer surface of the drill string 2100 near the drill bit 2151 that are timed together so as to extend at the same azimuth with relation to the well bore while the drill string 2100 is rotating. Each time an extendable pad 2150 extends, it pushes the drill bit 2151 off course and may be used to control the trajectory of the drill string 2100.

Yet another embodiment for steering a bit includes point-the-bit systems where a drill bit is actively positioned from further up a drill string.

Variations of these systems are disclosed in the following prior art documents. U.S. Pat. No. 5,529,133 to Eddison, which is hereby incorporated by reference for all that it contains, discloses a steerable rotary drilling tool that includes a drill bit mounted on the lower end of a housing by a drive shaft having an articulative coupling that allows the bit's rotation axis to be inclined relative to the rotation axis of the housing, an eccentric weight in the housing that maintains the bit axis pointed in only one direction in space as the bit is turned by the housing, and a clutch system that allows such direction to be changed downhole. A measuring-while-drilling tool is included to allow the progress of the drilling to be monitored at the surface and to allow changing the bit axis or toolface by a selected amount.

U.S. Pat. No. 5,078,650 to Foote which is herein incorporated by reference for all that it contains discloses a universal joint arrangement that includes a first adapter having two projecting support formations; a drive plate having a first pair of matching depressions or pockets is seated with these depressions on the projecting support formations of the first adapter and the drive plate has a second pair of pockets for the projecting support formations of a respective second adapter.

U.S. Pat. No. 7,188,685 to Downton which is herein incorporated by reference for all that it contains discloses a bottom hole assembly that is rotatably adapted for drilling directional boreholes into an earthen formation. It has an upper stabilizer mounted to a collar, and a rotary steerable system. The rotary steerable system has an upper section connected to the collar, a steering section, and a drill bit arranged for drilling the borehole attached to the steering section. The steering section is joined at a swivel with the upper section. The steering section is actively tilted about the swivel. A lower stabilizer is mounted upon the steering section such that the swivel is intermediate the drill bit and the lower stabilizer.

BRIEF SUMMARY OF THE INVENTION

In one aspect of the present invention, a drilling assembly includes a drill bit body disposed intermediate a working face and a shank. The shank may be attached to a drill string. The working face comprises an indenting member protruding from the working face, the indenting member being adapted to guide the drill bit. A flexible portion is disposed above the bit body to allow angular deflection of the bit with respect to the drill string.

The flexible portion may comprise upper and lower segments, and may be disposed intermediate, or between, the bit body and the shank or may be disposed intermediate, or between, the shank and an adjacent drill string component. The lower segment of the flexible portion may comprise an extension with a generally spherical distal end, and a corresponding spherical recess may be disposed in the upper segment. Bearing balls adapted to transfer torque may be retained in recesses and/or grooves in the spherical portions

of the upper and lower segments. In another embodiment, the flexible portion may comprise one or more universal joints. The flexible portion may comprise a compliant segment. The flexible portion may comprise a joint with laterally sliding surfaces.

The indenting member may be rotatable with respect to the bit body. A shaft may be disposed internal to the bit body and intermediate the indenting member and a rotating element such as a fluid-driven turbine, mud motor, or an electric motor. The shaft may be flexible, and may comprise a compliant portion, one or more universal joints, or a constant velocity joint.

The indenting member may comprise asymmetrical geometry on a distal end and a polycrystalline diamond cutting element. The polycrystalline diamond cutting element may comprise a pointed geometry.

The drilling assembly may comprise a mechanism adapted to selectively prevent movement of the flexible portion for drilling straight wellbores. The mechanism may be adapted to selectively limit angular deflection of the flexible portion, and may self-align the flexible portion to a position of zero angular deflection.

The drilling assembly may comprise a wiper seal disposed intermediate moveable sections of the flexible portion. The drilling assembly may also comprise a bellows-type seal disposed exterior to the flexible portion.

BRIEF DESCRIPTION OF THE DRAWINGS

FIG. 1a is a cross-sectional view of an embodiment of the prior art.

FIG. 1b is a cross-sectional view of another embodiment of the prior art.

FIG. 10a is a cross-sectional view of another embodiment of a drilling assembly.

FIG. 10b is another cross-sectional view of the embodiment of a drilling assembly in FIG. 10a.

FIG. 10c is a detailed view of the embodiment of a drilling assembly in FIG. 10a.

FIG. 11a is a cross-sectional view of another embodiment of a drilling assembly.

FIG. 11b is another cross-sectional view of the embodiment of a drilling assembly in FIG. 11a.

FIG. 12 is a cross-sectional view of another embodiment of a drilling assembly.

FIG. 13 is a cross-sectional view of another embodiment of a drilling assembly.

FIG. 14 is a cross-sectional view of another embodiment of a drilling assembly.

FIG. 15 is a diagram of an embodiment of a steering method.

DETAILED DESCRIPTION OF THE INVENTION AND THE PREFERRED EMBODIMENT

15 FIG. 1c discloses a drill string 100 suspended in a borehole 103 by a derrick 101. A drilling assembly 102a is connected to the end of the drill string 100 and comprises a drill bit 104a. As the drill bit 104a rotates the drill string 100 advances in the formation 105a. The drill string 100 may comprise one or 20 more flexible portions 209a to allow directional drilling.

FIG. 2 discloses an embodiment of a drilling assembly 102b. The drilling assembly 102b may comprise a drill bit 104b with a working face 106a, an indenting member 107a protruding from the working face 106a, and a shank 108a. A compliant segment 113 may be disposed intermediate, or between, the shank 108 and a portion of the drill string 109a. The compliant segment 113 may comprise a portion of reduced cross-section 110 to provide elastic angular deflection with respect to an axial centerline of the portion of the drill string 109a. Cross-sectional area may be reduced by a taper, a series of circumferential or axial grooves, or one or more helical grooves or via a more elastic material. The compliant segment 113 may be constructed from any material with sufficient strength and suitable elastic modulus, such as 30 high-strength steel or other metal or metal alloy. The drilling assembly 102b may comprise a shaft 111a intermediate, or between, the indenting member 107a and a rotating element 114a such as a fluid powered turbine, mud motor or an electric motor. The shaft 111a may comprise a compliant portion 112a to allow deflection in the shaft 111a corresponding to the deflection in the compliant segment 113.

The indenting member 107a may be asymmetric such that as it indents into the formation it leads the drill bit 104b away from a straight trajectory. The rotating element 114a above 45 may be used to position an apex of the indenting member 107a at a desired azimuth for the drill string 109a to follow. In such a manner, the driller may control the trajectory of the drill string 109a. In some embodiments, it may be desirable for the drill string 109a to drill in a straight trajectory; in such cases, the indenting member 107a may be randomly or otherwise rotated such that it leads the drill bit 104b in a straight direction.

The ability of the indenting member 107a to steer depends on the ability of the asymmetric indenting member 107a to 55 push off of the formation. In soft formations, the formation may push back on the indenting member 107a less. Thus, the compliant portion 112a may lower the amount of formation side push back on the indenting member 107a required to alter the path of the drill bit 104b.

FIG. 3 discloses a drilling assembly 102b according to the present invention. The drilling assembly 102b may comprise a drill bit 104c with a working face 106b, an indenting member 107b protruding from the working face 106b, and a shank 108b. The shank 108b is connected to a flexible portion 209a. The flexible portion 209a comprises an upper segment 210a and a lower segment 211a, the lower segment 211a comprising an extension 212a with a generally spherical portion 213.

The upper segment 210a comprises a generally spherical recess 214 corresponding to the generally spherical portion 213 of the lower segment 211a. The generally spherical portion 213 is moveably retained in the generally spherical recess 214. The generally spherical recess 214 comprises a plurality of reliefs 215 which hold a plurality of bearing balls 216. The generally spherical portion 213 of the lower segment 211a comprises a plurality of grooves 217, the bearing balls 216 extending into the grooves 217. The bearing balls 216 are free to slide or rotate in the grooves 217 and reliefs 215, thus allowing angular deflection of the lower segment 211a with respect to the upper segment 210a, while providing torque transmission through the flexible portion 209a as the drilling assembly 102b rotates. The bearing balls 216 may be retained in a bearing cage. The bearing balls 216 may be constructed from high strength steel and may be case hardened, heat treated, or otherwise processed to provide sufficient strength. Other suitable materials such as other metals, metal alloys, or ceramic may be used. The reliefs 215 and grooves 217 that retain the bearing balls 216 may also be heat treated, case hardened, or otherwise processed to mitigate abrasive wear.

The upper segment 210a may comprise a mechanism that selectively prevents movement of the lower segment 211a with respect to the upper segment 210a. In this embodiment, a plurality of stops 219a are disposed inside the upper segment 210a and may be brought into contact with the lower segment 211a, thus preventing angular deflection of the flexible portion 209a and allowing the drilling assembly 102b to drill a straight borehole. The plurality of stops 219a may be actuated by a mechanical, hydraulic, or electronic system or combinations thereof.

The upper segment 210a of the flexible portion 209a comprises a face 220 with a convex, generally spherical geometry, and the lower segment 211a comprises a face 221 with a concave, generally spherical geometry. The faces 220, 221 on the upper segment 210a and the lower segment 211a, respectively, have a common, substantially constant radius of curvature, with a center of curvature in the same location as a center of curvature of the generally spherical portion 213 and the generally spherical recess 214. The faces 220 and 221 are in slideable contact, thus allowing angular deflection of the lower segment 211a with respect to the upper segment 210a. The faces 220 and 221 may be heat treated, case hardened, or coated with a wear resistant material such as polycrystalline diamond, a low-friction material such as PTFE, or other wear resistant and/or low friction coating.

The drilling assembly 102b may also comprise a shaft 111b intermediate, or between, the indenting member 107b and a rotating element 114b, such as a fluid-powered turbine or electric motor. The shaft 111b may comprise a compliant portion 112b to allow deflection corresponding to the deflection of the flexible portion 209a.

Referring now to FIG. 4, the plurality of stops 219a are removed from contact with the lower segment 211a, thus allowing greater angular deflection 401 of the lower segment 211a with respect to the upper segment 210a. The indenting member 107b may comprise an asymmetrical geometry 402 on a distal end 803a. As the drilling assembly 102b rotates, the rotating element 114b rotates the shaft 111b with an angular velocity having the same magnitude but opposite direction of the angular velocity of the drilling assembly 102b. Thus, the indenting member 107b has zero angular velocity with respect to the formation 105b, and the asymmetrical geometry 402 on the distal end 803a guides the drill bit 104c through the formation 105b in an azimuth direction determined by the orientation of the indenting member 107b.

In some embodiments the flexible portion 209a is moved passively in consequence of the deflections caused by the indenting member 107b.

The plurality of stops 219 may selectively constrain the angular deflection 401 of the flexible portion 209a to any angle in an interval including zero angle, or non-deviated drilling, to the maximum angle attainable by the flexible portion 209a.

FIG. 5 discloses another embodiment of a drilling assembly 102c according to the present invention. In this embodiment, the drilling assembly 102c comprises a drill bit 104d comprising a working face 106c and a shank 108c. A flexible portion 209b is disposed intermediate, or between, the working face 106c and the shank 108c. The shank 108c is connected to a drill string 501.

FIG. 6 discloses an embodiment of a universal joint 601. The universal joint 601 comprises an inner portion 602 and an outer portion 603. The inner portion 602 is attached to the outer portion 603 by a spider 604a comprising bearing carriers 605a.

Referring now to FIG. 7a, a drilling assembly 102d comprises a drill bit 104e with a working face 106d and a shank 108d. The drill bit 104e comprises a flexible portion 209c intermediate, or between, the working face 106d and the shank 108d. The flexible portion 209c comprises an upper portion 701 and a lower portion 702, the lower portion 702 comprising an extension 703. A universal joint spider 604b comprises generally cylindrical bearing carriers 605b and is disposed such that an axial centerline 606 of the bearing carriers 605b intersects a center of curvature of a generally spherical interface 704. The bearing carriers 605b are held in bushings or bearings 607 in the upper portion 701 of the flexible portion 209c.

FIG. 7b discloses the same embodiment as FIG. 7a, with the drilling assembly 102d rotated 90 degrees. The universal joint spider 604b comprises generally cylindrical bearing carriers 608, an axial centerline 609 of which intersects the center of curvature of the generally spherical interface 704. Bearing carriers 608 extend into bushings or bearings 610 disposed in the extension 703 of the lower portion 702. The bushings 607 and 610 may be made from any suitable material including bronze, steel, Babbitt metal, or a polymer.

FIG. 8a discloses an embodiment of an indenting member 107c. In this embodiment, a polycrystalline diamond compact 801a is brazed or otherwise affixed to a distal end 803b of a shank 802a. The polycrystalline diamond compact 801a may be disposed coaxial to the shank 802a, and the polycrystalline diamond compact 801a may comprise pointed geometry 805. The shank 802a may be constructed from a steel alloy, and may be case hardened, heat treated, or otherwise processed to improve abrasion resistance. The shank 802a may comprise hard-facing.

FIG. 8b discloses another embodiment of an indenting member 107d. In this embodiment, a polycrystalline diamond compact 801b is brazed or otherwise affixed to a distal end 803c of a shank 802b. An axial centerline of the polycrystalline diamond compact 801b and an axial centerline of the shank 802b may be offset.

FIG. 8c discloses another embodiment of an indenting member 107e. A shank 802c comprises a distal end 803d which may be cast, machined, forged, or otherwise formed into a generally polygonal shape 820. The generally polygonal shape 820 may be asymmetric with respect to an axial centerline of the shank 802c.

FIG. 8d discloses another embodiment of an indenting member 107f. In this embodiment, the indenting member 107f comprises a shank 802d and a distal end 803e. The distal

end **803e** may comprise generally conical geometry **825**, and may be asymmetric with respect to an axial centerline of the shank **802d**. The distal end **803e** may comprise hard-facing or other material or treatment intended to reduce abrasive wear.

FIG. 9 discloses another embodiment of a drilling assembly **102e** according to the present invention. Drilling assembly **102e** comprises a flexible portion **209d** disposed intermediate, or between, a drill bit **104f** and a portion of drill string **109b**. The flexible portion **209d** comprises an interface **901** intermediate, or between, an upper segment **210b** and a lower segment **211b**. The interface **901** may be protected from abrasion and wear by a bellows-type cover **902**. The cover **902** may be made from electron-beam welded sheet metal or another material.

The interface **901** may comprise a seal **903** disposed intermediate the upper segment **210b** and the lower segment **211b**. The seal **903** may comprise an o-ring or wiper seal, and may be adapted to retain lubrication on the interface **901**. The interface **901** may be sealed from contact with drilling fluid or may be open to the drilling fluid.

A shaft **111b** may be disposed intermediate an indenting member **107g** and a rotating element **114c**. In this embodiment, the shaft **111b** comprises two universal joints **904** adapted to allow the shaft **111b** to deflect according to the deflection of the flexible portion **209d**.

FIG. 10a discloses another embodiment of a drilling assembly **102f**. In this embodiment, the drilling assembly **102f** comprises a flexible portion **209e** and includes a sliding collar **1001** comprising ports **1002**. Fluid passages **1003** are in communication with a plurality of pistons **1004**. The plurality of pistons **1004** are attached to mechanical stops **219b**.

Referring now to FIG. 10b, the ports **1002** in the sliding collar **1001** are now in communication with a plurality of fluid passages **1003**. Drilling fluid **1005** is diverted into and creates fluid pressure in passages **1003**.

Referring now to FIG. 10c, which is a detailed view of FIG. 10b, drilling fluid **1005** creates fluid pressure in the passages **1003** that forces the plurality of pistons **1004** and mechanical stops **219b** inward to contact a lower segment **211c** of the flexible portion **209e**. Flexible portion **209e** is thus immobilized to allow drilling of straight wellbores.

FIG. 11a discloses another embodiment of a drilling assembly **102g**. In this embodiment, a lower segment **211d** of a flexible portion **209f** comprises a threaded sleeve **1101** engaged with a threaded collar **1102**. The threaded sleeve **1101** is free to rotate on an extension **212b** of a lower segment **211d** of the flexible portion **209f**. An electric motor **1103** rotates the threaded sleeve **1101**, and alignment pins **1104** prevent the rotation of the threaded collar **1102**. As the electric motor **1103** rotates the threaded sleeve **1101**, the non-rotating threaded collar **1102** moves upward. Maximum angular deflection of the flexible portion **209f** can be controlled by adjusting the position of the threaded collar **1102**, and as the threaded collar **1102** moves upward it aligns the flexible portion **209f** to a position of zero angular deflection.

Referring now to FIG. 11b, the threaded collar **1102** is engaged with the rotatable threaded sleeve **1101**. The threaded collar **1102** is in its maximum upward position, effectively immobilizing the flexible portion **209f** to allow for straight drilling.

FIG. 12 discloses another embodiment of a drilling assembly **102h**. In this embodiment, a collar **1201** comprises a distal end **1202** with a generally conical geometry **1203**. A flexible portion **209g** comprises a lower segment **211e** with an extension **212c**, which also comprises generally conical geometry **1204**. The collar **1201** may be movable in a direction coaxial with an axial centerline **1205a** of the drilling assembly **102h**.

The position of the collar **1201** determines the maximum angular deflection of the lower portion **211e** of the flexible portion **209g**. The position of the collar **1201** may be controlled by a mechanical, electronic, hydraulic, or other system, or combinations thereof. As the collar **1201** moves toward the lower portion **211e** of the flexible portion **209g**, the generally conical geometries **1203** and **1204** are brought into mechanical contact and the lower portion of the joint **211e** self-aligns with the collar **1201** and the flexible portion **209g** reaches a position of zero angular deflection.

FIG. 13 discloses another embodiment of a drilling assembly **102i**. A drill bit **104g** comprises a plurality of grooves **1301** intermediate, or between, a working face **106e** and a shank **108e**. The grooves **1301** may be circumferential, helical, or otherwise oriented and may be machined, forged, cast, or otherwise formed in the drill bit **104g**. The grooves **1301** allow for elastic, angular deflections in the drill bit **104g**.

FIG. 14 discloses another embodiment of a drilling assembly **102j**. A flexible portion **209h** is disposed intermediate, or between, a drill bit **104h** and a portion of a drill string **109c**. The flexible portion **209h** comprises a compliant segment **1401** and an outer sleeve **1402**. A collar **1403** is moveable in a direction coaxial to an axial centerline **1205b** of the drilling assembly **102j**. Mechanical stops **1404** are disposed internal to the outer sleeve **1402**. The collar **1403** may selectively be brought into mechanical contact with the stops **1401**, thus limiting or disallowing angular deflection of the compliant segment **1401** and the drill bit **104h**.

FIG. 15 is a diagram of a method **2900** for steering a downhole tool string. The method comprises the steps of providing **2901a** drill bit assembly attached to an end of the tool string disposed within a bore hole; providing **2902** a shaft protruding from a working portion of the drill bit assembly, the working portion comprising at least one cutting element; engaging **2903** the formation with a distal end of the shaft, the shaft being part of the drill bit assembly; and angling **2904** the drill bit assembly with the shaft along a desired trajectory. The step of angling **2904** the drill bit assembly with the shaft may comprise angling the shaft or the step may include pushing the drill bit assembly along the desired trajectory with the shaft. It is believed that if the shaft is loaded with enough pressure that the shaft will penetrate the formation, but if the shaft does not overcome the formation pressure, then the shaft may move the drill bit assembly by pushing off of the formation. A narrow distal end may aid in concentrating the pressure loaded to the shaft into the formation such that it may overcome the formation pressure and penetrate the formation; on the other hand, a blunt or wide distal end may prevent the shaft from penetrating the formation and allow the shaft to push off of the formation. In some embodiments, the shaft may advance along the desired trajectory before the drill bit assembly. The shaft may be at least partially disposed within a chamber generally coaxial with the shank portion of the assembly and the chamber may be disposed within a body portion of the assembly. Angling **2904** the drill bit assembly may be controlled over a downhole network.

In some embodiments, the shaft is rotationally isolated from the working portion of the drill bit assembly. This may be advantageous because it allows the shaft to remain on the desired trajectory even though the remainder of the drill bit assembly is rotating. In some embodiments of the method, the shaft may also rotate with the body portion of the drill bit assembly if there is a plurality of actuators timed to temporally move the shaft such that the distal end of the shaft stays on the desired trajectory.

Whereas the present invention has been described in particular relation to the drawings attached hereto, it should be

understood that other and further modifications apart from those shown or suggested herein, may be made within the scope and spirit of the present invention.

What is claimed is:

1. A method for steering a downhole tool string through a formation, comprising:
  - positioning a drill bit adjacent a drill string component, the drill bit including:
    - a working face;
    - a shank;
    - a bit body between the working face and the shank;
    - an indenting member having a distal end protruding from the working face;
  - a flexible portion disposed above the bit body between the shank and the adjacent drill string component, the flexible portion including an upper segment and a lower segment; and,
  - at least one of an o-ring disposed between the upper segment and the bit body, a wiper seal disposed between the upper segment and the bit body, and a bellows-type seal disposed exterior to the flexible portion;
  - positioning the drill string component and the drill bit in a bore hole; and,
  - orienting the indenting member in a desired trajectory.
2. The method of claim 1, further comprising rotating at least one of the drill string component and the drill bit.
3. The method of claim 1, further comprising rotating the drill bit in a direction and rotating the indenting member in another direction opposite the direction that the drill bit rotates.
4. The method of claim 1, further comprising pushing the indenting member against the formation.
5. The method of claim 1, wherein orienting the indenting member in a desired trajectory further comprises at least one of orienting the indenting member in a desired azimuth and angling the distal end of the indenting member.
6. A method for steering a downhole tool string through a formation, comprising:
  - positioning a drill bit in a bore hole, the drill bit including:
    - a working face;
    - a shank;
    - a bit body between the working face and the shank;
    - an indenting member having a distal end protruding from the working face; and,
    - a flexible portion disposed above the bit body, the flexible portion including:
      - a lower segment that includes an extension with a generally spherical geometry on a distal end; and,
      - an upper segment that includes a generally spherical recess that corresponds with the generally spherical geometry of the lower segment; and,
    - positioning the indenting member in a desired trajectory.
  7. The method of claim 6, further comprising rotating the drill bit in a direction and rotating the indenting member in another direction opposite the direction that the drill bit rotates.
  8. The method of claim 6, further comprising pushing the indenting member against the formation.
  9. The method of claim 6, wherein positioning the indenting member in a desired trajectory further comprises at least one of orienting the indenting member in a desired trajectory,

orienting the indenting member in a desired azimuth, and angling the distal end of the indenting member.

10. A method for steering a downhole tool string through a formation, comprising:
  - positioning a fluid-driven turbine and a drill bit in a bore hole, the drill bit including:
    - a working face;
    - a shank;
    - a bit body between the working face and the shank;
    - an indenting member having a distal end protruding from the working face; and,
    - a flexible portion disposed above the bit body, the flexible portion including:
      - a lower segment;
      - an upper segment; and
      - an interface between the lower and upper segment, the interface including at least one of an o-ring and a wiper seal to create a seal; and,
    - positioning the indenting member in a desired trajectory.
  11. The method of claim 10, further comprising rotating the drill bit in a direction and rotating the indenting member in another direction opposite the direction that the drill bit rotates.
  12. The method of claim 10, further comprising pushing the indenting member against the formation.
  13. The method of claim 10, wherein positioning the indenting member in a desired trajectory further comprises at least one of orienting the indenting member in a desired trajectory, orienting the indenting member in a desired azimuth, and angling the distal end of the indenting member.
  14. A method for steering a downhole tool string through a formation, comprising:
    - positioning a drill bit in a bore hole, the drill bit including:
      - a working face;
      - a shank;
      - a bit body between the working face and the shank;
      - an indenting member having a distal end protruding from the working face; and,
      - a flexible portion disposed above the bit body, the flexible portion including:
        - a lower segment;
        - an upper segment; and,
        - an interface between the lower and the upper segment;
        - and,
        - a bellows-type cover disposed exterior to the flexible portion; and,
      - positioning the indenting member in a desired trajectory.
    15. The method of claim 14, further comprising rotating the drill bit in a direction and rotating the indenting member in another direction opposite the direction that the drill bit rotates.
    16. The method of claim 14, further comprising pushing the indenting member against the formation.
    17. The method of claim 14, wherein positioning the indenting member in a desired trajectory further comprises at least one of orienting the indenting member in a desired trajectory, orienting the indenting member in a desired azimuth, and angling the distal end of the indenting member.
